UNITED STATES PATENT OFFICE.

HERMAN J. SUIB, OF NEW YORK, N. Y.

COMPOSITION FOR TREATING FABRIC.

No Drawing.

Application filed February 7, 1922. Serial No. 534,802.

To all whom it may concern:

Be it known that I, HERMAN J. SUIB, a citizen of the United States, and a resident of the city of New York, borough of the Bronx, in the county of Bronx and State of New York, have invented a new and Improved Composition for Treating Fabric, of which the following is a full, clear, and exact description.

10 The present invention relates to new and useful improvements in treating fabric, and it pertains more particularly to a method of treating fabric for rendering the same translucent.

15 It is one of the objects of the invention to provide a fabric which is especially adapted for use in the manufacture of lamp shades, and while the fabric is especially adapted for this purpose it is also capable 20 of use in other connections as well.

In carrying out the process, gelatine and water are boiled together in the proper proportions to produce a fluid mass of a consistency capable of being spread by means 25 of a brush or similar implement. After this has been accomplished, yeast and alum and acetate of lead are added to the composition. The gelatine employed in the composition gives the necessary body to the liquid which is transparent, and at the same time, serves to fill the interstices in the fabric when the compound is applied thereto. The action of the yeast in the compound is to prevent undue shrinking of the fabric during the drying process. The alum serves

to render the composition more or less fire-proof in nature as does also the acetate of lead.

In treating the fabric the composition is spread thereover in any suitable manner and 40 in the manufacture of lamp shades the fabric so saturated with the composition is stretched over the shade frame in a wet state. The fabric, however, may be stretched prior to the treatment thereof if desired. 45

During the drying process the fabric shrinks to the frame, and after the drying process is completed, the whole is covered with a suitable waterproof transparent varnish. 50

From the foregoing it is apparent that the present invention provides a new and useful method of treating fabrics for rendering the same translucent, and, at the same time, produces an article of manufacture especially adapted for the purpose of making lamp shades. 55

What is claimed is:

1. A composition for treating fabrics to render said fabrics translucent, said composition comprising gelatine, water, yeast and alum. 60

2. A composition for treating fabrics to render the same translucent, consisting of a mixture of gelatine, water, yeast and alum, 65 the gelatine and water being first mixed together to the proper consistency, after which the yeast and alum are added.

HERMAN J. SUIB.
